United States Patent Office

Des. 188,275
Patented June 28, 1960

188,275

CARPORT OR SIMILAR ARTICLE

Nicholas A. Vetere, Pompton Plains, N.J., assignor to Awnair Corporation of America, Haskell, N.J.

Filed Jan. 24, 1958, Ser. No. 49,395

Term of patent 3½ years

(Cl. D13—1)

FIG. 1

Figure 1 is a front perspective view of a carport or similar article showing my new design;

I claim:

The ornamental design for a carport or similar article, substantially as shown and described.
